UNITED STATES PATENT OFFICE.

JESSE H. PRESCOTT, OF MEDFORD, MASSACHUSETTS, ASSIGNOR TO WILLIAM K. LOGEE,
OF PROVIDENCE, RHODE ISLAND.

DRAFT-CONTROLLING DEVICE FOR FURNACES.

Application filed July 28, 1919. Serial No. 213,736.

To all whom it may concern:

Be it known that I, JESSE H. PRESCOTT, a citizen of the United States, residing at Medford, in the county of Middlesex, State 5 of Massachusetts, have invented certain new and useful Improvements in Draft-Controlling Devices for Furnaces, of which the following is a specification.

My invention is an improved apparatus 10 for controlling the forced draft of steam-boiler or other furnaces, whereby the current of air, or air and steam, is automatically shut off when the firing-door of the furnace is opened; and immediately supplied again 15 upon the closing of the door. Through this automatic control of the forced draft "flare-back" through the firing-doors is avoided, and more important, the fine particles of partly consumed fuel are prevented from 20 being blown up the flue and wasted; while the temperature in the combustion chamber or fire box is maintained more nearly at maximum by preventing the cooling off of the fire under a sudden inrush of air.

The object of my improvement is to provide a simpler and more efficient apparatus 25 for the purpose above described, which may be applied to practically all types of furnaces without material change or alteration 30 in the organization thereof, and which when once installed will operate automatically without adjustment or other attention. A further object of the improvement is to render the device operative from the movement 35 of the firing-doors of the furnace without the need of other motive power, and without requiring electro-magnetic or other complicated actuating means.

The manner and means for carrying out 40 these improvements are fully described in the following specification, illustrated by the accompanying drawings, in which like reference characters indicate like parts. In the drawings:

Fig. 1 is a front elevation of a steam-boiler furnace, showing my improved draft-controlling device applied to use thereon;

Fig. 2, an enlarged detail view of the operating mechanism for the shut-off valve of 45 the draft-blower;

Fig. 3, an elevation of the balanced weighted lever which furnishes the power to operate the shut-off valve;

Fig. 4, a detail view of the crank-connection between the firing-door and weighted lever; and

Fig. 5, a view in reduced scale showing a modified arrangement of the connections between the firing-door and valve-operating lever.

Referring first to Fig. 1, A designates the boiler front which is usually set in masonry M, while beneath the boiler are two firing-doors F—F' and two lower ash-pit doors E—E'. At the side of the boiler furnace, or 55 arranged in any other convenient location, is a power-actuated blower B or forced draft appliance which communicates with the ash-pit to supply a current of air beneath the furnace grate. The blower B may be of any 60 suitable construction as usually employed for this purpose and is preferably driven by steam pressure from the boiler, although it might be operated from any other source of power such as an electric motor. The blower 65 may operate on the suction fan principle or with a jet of steam, its detail of construction not being shown in the present drawings since such types of apparatus are well 70 known to those versed in the art. Suffice it 75 to state that the blower B is operated under steam pressure communicated through a pipe P connected thereto at p and communicating with the boiler at any convenient point, not herein shown. The steam pressure in the 80 pipe P is regulated by an overhead valve V which is controlled through a system of cords and pulleys, as indicated at G, leading 85 to the main damper in the flue at the rear of the furnace. These connections, however, 90 not being essential to the operation of the present apparatus are not herein described 95 and illustrated in detail.

At the side of the boiler is a hand-valve H for manual control of the steam pressure 95 supplied through the pipe P to the blower B, and just below the hand-valve is the automatically operated shut-off valve K. As shown more particularly in Fig. 2, the valve K is of the well known "balanced" type having two opposite ports 2 and 3 adapted to be closed by gates or plugs 4 and 5 carried by a sliding stem 6. The stem 6 is operated from a lever 8 having its lower end pivotally connected at 9 to a link 10 which is hinged 100 to the side of the valve casing. Above its

pivot 9 the lever 8 is connected to a yoke 11 on the end of the stem 6 and is guided in its movement between the ends of a forked arm 12 rigidly supported from the valve 5 casing. Pivotedly connected to the upper end of the lever 8 by means of a yoke 14 is a horizontal rod 15 which is operated from the balanced weighted lever 16. The weighted lever 16 is preferably arranged within a segment-shaped casing or box 17, see also Fig. 3, to protect it from accidental displacement and prevent interference with its action, the casing being conveniently located on the front of the boiler or its setting as illustrated in 10 Fig. 1. Closing the front of the casing 17 is a removable cover-plate 18 held in place by suitable screws 19. On the rear wall of the casing 17 is a boss 20, see Fig. 3, from which projects a stud 21 providing the fixed 15 pivot for the weighted lever 16 which is formed with a hub 22 bored to receive the stud. The main arm of the lever 16 extends upwardly from its hub 22 and carries the cylindrical weight 23 at its upper end, while 20 below the weight is a cylindrical-headed stud 24 reaching through the arm and held in place thereon by a pin 25 at its rearward end. The head of the stud 24 is formed with a transverse bore 26 through which 25 the rod 15 is loosely inserted. As shown in Fig. 2, the rod 15 is screw-threaded from its outer end throughout the greater part of its length, and on opposite sides of the stud 24 are stop-nuts 27 and 28 screwed onto 30 the threads. The nuts 27 and 28 are arranged in pairs so that one may be set up against another to lock them in place in the manner of check-nuts. As before indicated, the rod 15 is free to slide through the bore 35 of the headed stud 24 when the weighted lever 16 is moved from one position to the other as indicated by the full lines and dash lines in Fig. 2. When, however, the stud 24 comes into engagement with either set 40 of nuts 27 or 28 on the rod 15 the latter will be moved by the weighted lever 16 to operate the lever 8 to open or close the valve K, as the case may be. The nuts 27 and 28, being adjustable along the rod 15, 45 provide for setting the mechanism so that the valve action takes place only at the extreme end of the throw of the weighted lever 16 in either direction.

The weighted lever 16 is shifted across 50 the vertical plane of its axis of rotation, by means of a rockable bell-crank lever 29. The bell-crank 29 acts on the weighted lever 16 to initiate its movement to carry it across center, whereupon its motion is continued 55 solely through the action of gravity. In this way the weighted lever is caused to act on the valve-lever 16 by gravity to secure a quick closing or opening of the valve, there being lost-motion between the weighted lever 60 16 and the actuating rod 15 as provided for

by the sliding of the rod through the stud 24. The bell-crank 29 is provided with a hub 30 pivoted on the outer end of the stud 21, and held in place by the cover 18 of the casing 17. Projecting from the left-hand side of the hub, as viewed in Fig. 2, is a horizontal arm 31, from the end of which is suspended a counterweight 32 which tends to normally maintain the bell-crank 29 in the position shown by full lines in Fig. 2. 70 The arm 31 is continued across the top of the hub 30 in the shape of a quadrant having its central portion cut away to form two spaced, upstanding lugs or contact-shoulders 33-34. The shoulders 33-34 are adapted 80 to engage the sides of a lug 35 which projects from the front of the arm of the weighted lever 16. It will thus be seen by reference to Fig. 2 that when the bell-crank 29 is rocked in either direction it acts through 85 one of the shoulders 33 or 34 to shift the weighted lever 16 across center, after which the latter is free to be moved by gravity until its lug 35 strikes the opposite shoulder on the bell-crank. 90

The bell-crank 29 is connected to be operated from the firing-doors F-F' of the furnace by means of a horizontal rod 36 which is connected to its vertical arm 37. Referring particularly to Fig. 3, the hub 30 of 95 the bell-crank 29 carries a stud 38 projecting through an opening in a boss 39 on the front of the cover 18 of the casing 17. The outer end of the stud 38 is squared off on its sides, see also Fig. 2, and fitted to a square 100 bore in the hub 40 of the arm 37. A washer 41 is held against the outer end of the hub 40 by a screw 42 screwed into the stud 38 to secure the arm 37 fast with the main hub 30 of the bell-crank with the inner end of the hub 40 bearing against the boss 39. At its lower end the arm 37 is pivotally connected to a yoke 43 on the end of the connecting-rod 36 which extends across the front of the boiler above the firing-doors F-F'. The 105 rod 36 is slidable through bearings 44-44 on the sides of two casings 45-45 which are attached to the boiler front B above the hinges of the firing-doors F-F' as shown in Fig. 1. Each casing 45 is provided with a 110 bearing 46 on its bottom in which is journaled a vertical shaft or rod 47, see Fig. 2, carrying a crank-arm 48 at its upper end. At the end of the crank 48 is a stud 49 on which is journaled a roller 50 adapted to 115 engage with and ride along the face of a cam-plate or crosshead 51 secured on the connecting-rod 36 and extending laterally thereof as shown in Fig. 4. The shaft 47 forms an extension of and is connected to the 120 upper end of the hinge-rod 52 of the firing door F' by means of a coupling 53 shown in Fig. 2. This latter consists of two collars 54-54 keyed to the ends of the two rods 47-52 or secured thereon by set screws 55 125 130

and having a key and slot connection 56 at their ends. Through this arrangement the rods 47—52 are connected to be rotated together from the movement of the firing-door 5 F', the rod 52 being held fast in the hinges f—f of the latter by splines or set-screws 57, see Figs. 1 and 2. It has been explained that there are two casings 45, one above each firing-door, and their arrangement and connection with the hinge-rods 52 are substantially the same. The operating rod 36 may extend continuously between the two casings, but is preferably formed of sections connected by turnbuckles or adjusting nuts 10 58—58 as shown in Fig. 1. This arrangement allows for adjusting the length of the rod in accordance with variations in the distance between the door-hinges and also provides a more or less flexible connection between the end-sections of the rods to take care of inaccuracies in the alinement of the bearings. The rod 36 may be extended for connection with any number of firing-doors and, preferably, it carries a collar 62, see 20 25 Figs. 2 and 4, which is adapted to strike against the bearing 44 on one of the casings 45 to limit the sliding movement of the rod to the right.

Fig. 4 of the drawings shows the right-hand casing 45 with the crank-motion for the right-hand firing-door F' and, as before stated, the arrangement of the left-hand casing for the door F is the same. It will be noted from Fig. 4 that normally, with 30 35 the firing-door closed, the crank-arm 48 assumes a position in alinement with the connecting-rod 36 as shown by the full lines in this view. Therefore, when the door F' is swung outwardly on its hinges to open it it will rotate the rod 52 and shaft 47 to turn the crank 48 inwardly toward the boiler, as indicated by the dash lines in Fig. 4. This action causes the roller 50 at the end of the crank-arm 48 to come into engagement with 40 45 the side of the crosshead 51, and riding there along it will slide the connecting-rod 36 to the left as indicated by the dash lines in Fig. 4. The same action takes place when the left-hand firing-door F is swung open on its hinges, except that in this case the crank-arm 48 turns outwardly away from the boiler, but its effect on the crosshead 51 is the same and the rod 36 will be slid to the left.

Fig. 5 illustrates a modification in the arrangement for connecting the sliding rod 36 with the bell-crank 30 which operates the weighted lever 16. In some cases, where the automatic shut-off valve for the steam pressure blower B is located at the left-hand side of the boiler it is necessary to reverse the direction of action of the controlling mechanism. For this purpose the sliding connecting-rod 36 may be arranged to move 50 55 60 65 to the right by reversing the position of the

crank-motion parts, and the end of the rod is then connected to the horizontal arm 31 of the bell-crank 29 by means of a cord or chain 60 passing over a pulley 61. This mode of connecting the slide rod 36 with 70 the weight-operating means may also be employed where the blower is located in a more remote position, around a corner or at a higher or lower level than the door-operated means. In other instances, where the doors are hinged to swing on a horizontal axis their crank-motions may be arranged to operate a vertically slideable rod connected to the arm 31 of the bell-crank 29.

The method of operation of the complete apparatus is as follows: The device may be applied to use on practically all types of furnaces using forced draft and its mechanism may be installed without material fitting or alteration of the original plant. All that is required is to break into the steam-pipe P with the automatic shut-off valve K, and to attach the controlling mechanism to the front of the boiler in connection with the firing-doors F—F'. With the apparatus installed in the manner as above described the mechanism operates as next explained: When either of the firing-doors F—F' is opened for any purpose, as for inspecting, stoking or raking the fire, the turning of its hinges will cause the hinge-rod 52 and its connected shaft 47 to be rotated. The rotation of the shaft 47 swings the crank-arm 48 to bring its roller 50 against the crosshead 51 on the connecting-rod 36. It will be noted from Figs. 2 and 4 of the drawings that there is a slight amount of lost-motion between the crank 48 and the crosshead 51 so that the door may be opened to a limited extent before the roller 50 starts to act on the crosshead. The crosshead 51 may be adjusted along the rod 36 to regulate the amount of this lost-motion and usually it is set so that after the door has been swung open to an appreciable degree the roller 50 will engage the crosshead 51 and, as the movement of the crank-arm 48 is continued, will then act to slide the rod 36 to the left. This sliding movement of the rod 36 acts to rock the bell-crank 29 on its pivot 21 against the action 100 105 110 115 of its weight 32. As the bell-crank 29 is thus moved in the direction indicated by the arrow a, Fig. 2, its contact-shoulder 33, bearing against the lug 35 on the weighted lever 16, will swing the latter on its pivot in the same direction. This action is continued by the opening of the firing-door until the center of the weight 32 is carried across the vertical plane of the axis of the lever 16, at which point the force of gravity will cause 120 125 130 the weighted lever to drop to the right until its lug 35 strikes against the opposite contact-shoulder 34 on the bell-crank 29. This latter movement of the weighted lever 16 is relatively quicker than its initial motion and

as it drops to the position indicated by the dash lines in Fig. 2 its stud 24, sliding along the rod 15, strikes against the stop-nuts 28 and thereby moves the rod to the right. This movement of the rod 15 causes the valve-controlling lever 8 to be swung to the right to slide the valve-stem 6 into the casing of the valve K to close the gates 4 and 5 against its ports. In this way the valve K is closed 10 with an abrupt action to shut off the steam pressure from the blower B so that the latter will cease to function. The weighted lever 16 continues to act through gravity to maintain the valve K closed as long as either of 15 the firing-doors remains open, and hence the forced draft is cut off so that it cannot cause a flare-back through the door. Moreover, the shutting off of the draft prevents the fine particles of fuel which are under partial 20 combustion from being blown up the flue, due to the sudden inrush of air through the firing-door. In this way the device not only provides a measure of safety in the operation of the furnace, but, furthermore, and more 25 important it is of material benefit in conserving fuel and saving steam by preventing the sudden cooling of the fire.

When the inspection or tending of the fire is completed the closing of the door acts to 30 again start the operation of the blower in the manner as next explained: As the door F or F' is swung to on its hinges the rod 52 and its connected shaft 47 are rotated to turn the crank-arm 48 back to first position, as 35 illustrated by the full lines in Fig. 4. This action releases the pressure of the roller 50 against the crosshead 51 and the rod 36 is thereby allowed to slide to the right under the impulse of the counterweight 32 on the 40 arm 31 of the bell-crank 29. It will be noted from reference to Fig. 2 that the counterweight 32 has a greater leverage on the bell-crank 29 than that of the weighted lever 16, whereby the latter is moved from the counterweight 45 to swing it to its mid position. That is to say, the engagement of the shoulder 34 on the bell-crank 29 with the lug 35 on the weighted lever 16 causes the latter to be swung to the left under the action of the 50 counterweight 32. When the weighted lever 16 is thus shifted across the vertical plane of its axis of rotation the force of gravity once more comes into play to cause it to swing into first position as illustrated by the full lines in 55 Fig. 2. As the lever 16 drops to this position its lug 35 strikes against the contact-shoulder 33 on the bell-crank 29 to prevent it from further movement, the movement of the bell-crank 29 under the action of its 60 weight 32 being limited by the rod 36 as controlled by its stop-collar 62 before described. Meanwhile, as the weighted lever 16 swings back to first position its stud 24 brings up against the stop-nuts 27 on the rod 65 15, and acting therethrough moves the rod

to the left to swing the lever 8 in the same direction. This latter action causes the valve-stem 6 to be slid to the left to withdraw the plugs 4 and 5 from the ports of the valve K so that the latter is opened by a 70 quick movement to admit the steam pressure to the blower B. In this way the blower is caused to function again to supply the forced draft to the fire immediately the firing-door is closed. 75

It will be observed that the mechanism of my improved device is extremely simple in construction and method of operation, efficient in action, and proof against derangement or getting out of order. It may be applied to use with practically all types of forced draft furnaces without reconstruction or rearrangement of the parts thereof and when once installed operates automatically without adjustment or setting. It is further 80 to be noted that the device is operated from the movement of the firing-doors without the need of motive power, other than the gravity of its balance weight, yet its action is quick and positive in opening and closing the 85 steam pressure valve which supplies power to the blower. 90

Various modifications might be made in the structure and arrangement of the parts of my improved device without departing 95 from the spirit or scope of the invention; therefore, without limiting myself to the precise embodiment herein shown and described, what I claim is:

1. In a draft-controlling device for furnaces, the combination with means for supplying forced draft to the fire, of means to arrest the draft, a pivoted weighted lever for operating the draft-arresting means, and means operated by the opening of the firing-door to shift the weighted lever across the vertical plane of its axis of rotation to cause it to act through gravity to operate the draft-arresting means. 100

2. In a draft-controlling device for furnaces, the combination with a blower for supplying forced draft to the fire, of means for operating the blower, means to stop the action of the blower, a pivoted weighted lever for actuating the stopping means, and means operated by the opening of the firing-door of the furnace to shift the weighted lever across the vertical plane of its axis of rotation to cause it to act on the stopping means by gravity. 105

3. In a draft-controlling device for furnaces, the combination with a power-operated blower for supplying forced draft to the fire, of means for starting and stopping the blower, a pivoted weighted lever controlled by gravity to operate said starting and stopping means, and means connected to the firing-door of the furnace to shift the weighted lever across the vertical plane of its axis to cause it to act by gravity to stop 115 120 125 130

the blower when the door is opened and to start the blower when the door is closed again.

4. In a draft-controlling device for furnaces, the combination with a steam pressure operated blower for supplying forced draft to the fire, of a valve for controlling the operation of the blower, a gravity-controlled pivoted weighted lever for operating the valve, and means connected with the firing-door of the furnace to shift the weighted lever across the vertical plane of its axis to cause it to close the valve when the door is opened and to open the valve when the door is closed again.

5. In a draft-controlling device for furnaces, the combination with a power-actuated blower for supplying forced draft to the fire, of means to control the power to start and stop the blower, a gravity-actuated pivoted weighted lever for operating the power-controlling means, and means operated from the opening and closing of the firing-door of the furnace to initiate a movement of the weighted lever in one direction or the other whereby the force of gravity will cause it to act on the power-controlling means to stop or start the blower.

6. In a draft-controlling device for furnaces, the combination with a power-actuated blower for supplying forced draft to the fire, of means for controlling the power to start and stop the blower, a pivoted weighted lever for actuating the power-controlling means, and means operated by the opening and closing of the firing-door of the furnace to shift the weighted lever across the vertical plane of its axis to cause it to act in opposite directions through gravity to actuate the power-controlling means.

7. In a draft-controlling device for furnaces, the combination with a power-actuated blower for supplying forced draft to the fire, of means movable in opposite directions to start and stop the blower, a pivoted weighted lever arranged to act through gravity to shift said starting and stopping means, and means operated from the opening and closing of the firing-door of the furnace to initiate the movement of the weight across the vertical plane of its axis to shift it into position to be further actuated by gravity.

8. In a draft-controlling device for furnaces, the combination with a blower for supplying forced draft to the fire, of means shiftable in opposite directions to start and stop the blower, a pivoted weighted lever for shifting said starting and stopping means, and means operated from the opening and closing of the firing-door of the furnace to throw the weighted lever across the vertical plane of its pivotal axis to cause it to be acted upon by gravity to operate on the starting and stopping means.

9. In a draft-controlling device for furnaces, the combination with a blower for supplying forced draft to the fire, of means shiftable in opposite directions to start and stop the blower, a member for shifting said means, stops on said member, a pivoted weighted lever shiftable in opposite directions to engage said stops to move the member, and means operated from the opening and closing of the firing-door of the furnace to throw the weight across the vertical plane of its axis whereby it will act on the shifting-member by gravity.

10. In a draft-controlling device for furnaces, the combination with a draft appliance for supplying forced draft to the fire, of means to control the operation of the draft appliance, a gravity-controlled pivoted weighted lever for operating the draft-controlling means, a bell-crank for shifting the weighted lever across the vertical plane of its axis to cause it to be acted upon by gravity to operate the starting and stopping means, and means for connecting the bell-crank to be operated from the opening and closing movement of the firing-door of the furnace.

11. In a draft-controlling device for furnaces, the combination with a forced draft appliance, of means to control the operation of the draft appliance, a gravity-controlled pivoted weighted lever for operating the draft-controlling means, a bell-crank connected to be operated from the opening and closing movement of the firing-door of the furnace, and means connecting the bell-crank to the weighted lever to shift the latter across the vertical plane of its axis while allowing lost-motion therebetween to cause the weighted lever to act on the draft-controlling means by gravity.

12. In a draft-controlling device for furnaces, the combination with means for supplying forced draft to the fire, of means for starting and stopping the operation of the draft-supplying means, a pivoted weighted lever for operating the starting and stopping means, a slidable member for shifting said weighted lever in opposite directions to cause it to be further actuated by gravity, and a crank-mechanism operated by the movement of the firing-door of the furnace to slide the weight-shifting member.

13. In a draft-controlling device for furnaces, the combination with means for supplying forced draft to the fire, of means for starting and stopping the operation of the draft-supplying means, a pivoted weighted lever for operating the starting and stopping means, a slidable member for shifting said weighted lever across the vertical plane of its axis to cause it to be operated upon by gravity, a crosshead on said member, and a crank connected to be rotated from the movement of the firing-door of the furnace.

6
to engage the crosshead to slide the shifting-member.

14. In a draft-controlling device for furnaces, the combination with means for supplying forced draft to the fire, of means for starting and stopping the operation of the draft-supplying means, a pivoted weighted lever for operating the starting and stopping means, a bell-crank having opposed contact-shoulders for engaging the weighted lever to shift it in opposite directions while allowing lost motion therebetween, and means connected to the firing-door of the furnace to rock the bell-crank to shift the weighted lever across the vertical plane of its axis whereby it is acted upon by gravity to operate the starting and stopping means.

15. In a draft-controlling device for furnaces, the combination with means for supplying forced draft to the fire, of means for starting and stopping the operation of the draft-supplying means, a pivoted weighted lever for operating the starting and stopping means, a bell-crank for shifting the weighted lever across the vertical plane of its axis, a connecting-rod for rocking the bell-crank, a crosshead on said rod, and a crank-arm operated by the movement of the firing-door of the furnace to engage the crosshead to slide the connecting-rod.

16. An automatic draft-regulating device for furnaces comprising a draft-controlling member, a pivoted weighted lever adapted to be shifted across the vertical plane of its axis to cause it to act by gravity on the controlling-member, and means operable from the movement of the firing-door of the furnace to initiate the movement of the weighted lever against the action of gravity.

40 17. An automatic draft-regulating device for furnaces comprising a pivoted weighted lever, a draft-controlling member movable from said weighted lever, adjustable stops on said controlling-member, means on the

weighted lever for engaging said stops, and 45 means operable from the movement of the firing-door of the furnace to swing the weighted lever across the vertical plane of its axis to cause it to engage the stops on the controlling-member to operate the latter 50 by gravity.

18. An automatic draft-regulating device for furnaces comprising a steam pressure shut-off valve, a controlling-member for operating said valve, a pivoted weighted 55 lever adapted to operate on said controlling-member under the action of gravity to open and close the valve, and means operable from the movement of the firing-door of the furnace for initiating the movement of the 60 weighted lever across the vertical plane of its axis whereby it is caused to act in opposite directions on the valve-controlling member.

19. An automatic draft-regulating device 65 for furnaces comprising a draft-controlling member, a rod connected to move said controlling-member, stops on said rod, a pivoted weighted lever movable across the vertical plane of its axis to engage it with the stops 70 on the rod, and means adapted for connection with the firing-door of the furnace to shift the weighted lever in opposite directions.

20. An automatic draft-regulating device 75 for furnaces comprising a draft-controlling member, a pivoted weighted lever for acting by gravity on the controlling-member, a bell-crank having means for engaging the weighted lever to shift the latter in opposite 80 directions across the vertical plane of its axis, a connecting rod for operating the bell-crank, and means adapted for connection with the firing-door of the furnace to slide the rod from the movement of the door. 85

In testimony whereof I affix my signature.

JESSE H. PRESCOTT.
